UNITED STATES PATENT OFFICE.

WILLIAM G. RESTORFF AND MILTON M. LILE, OF WASHINGTON, DISTRICT OF COLUMBIA, ASSIGNORS, BY DIRECT AND MESNE ASSIGNMENTS, OF ONE-HALF TO SAID RESTORFF AND ONE-HALF TO JOSEPH C. CARDWELL, OF WASHINGTON, DISTRICT OF COLUMBIA.

CRUTCH ATTACHMENT.

1,132,119.

Specification of Letters Patent. Patented Mar. 16, 1915.

Application filed January 23, 1914. Serial No. 813,957.

To all whom it may concern:

Be it known that we, WILLIAM G. RESTORFF and MILTON M. LILE, citizens of the United States, residing at Washington, in the District of Columbia, have invented certain new and useful Improvements in Crutch Attachments, of which the following is a specification.

This invention relates to crutches, and 10 has as its object to provide a convertible tip for a crutch, adapting the crutch for use in both summer and winter.

Crutch tips of the type designed especially for use to prevent slipping on icy surfaces, are ordinarily provided with spurs or their tread surfaces are serrated. Where spurs are employed, but a minimum bearing or tread surface is afforded, and, when the spurs contact with the pavement after 20 penetrating the ice or snow, they are liable to slip. Where the tip is provided with a serrated tread surface, an effective bearing or tread area is provided, in most instances, but the spaces between the serrations are 25 liable to become clogged with snow and the tip then becomes ineffective. Furthermore, a serrated surface is likely to become worn smooth in a short time, rendering the tip even dangerous to use.

30 It is therefore one aim of the invention to so construct the tip that when adapted for use upon icy surfaces, a maximum bearing or tread area will be provided, although the tip is adapted to penetrate the ice or 35 snow to a maximum depth and be prevented from slipping.

Another aim of the invention is to so construct the tip that snow and ice cannot pack therein, and so that any accumulated ice or 40 snow will be automatically dislodged as the tip is brought into engagement with the surface of the ground.

Incidentally, the invention contemplates so constructing this portion of the tip that 45 should it, for any reason, become clogged, the accumulated matter will be dislodged without removing the tip from the crutch.

The invention further aims to so form the tread end of the tip that should it become 50 dulled it may be readily and repeatedly sharpened until considerably worn down without detracting from the convertibility of the tip.

A further aim of the invention is to so

construct the tip that it may be readily 55 converted from one to the other of its forms without the use of tools.

In the accompanying drawings: Figure 1 is a perspective view of a portion of a crutch staff equipped with the tip embodying the present invention, and adapted for use on icy surfaces. Fig. 2 is a vertical sectional view through the tip showing Fig. 1, the end of the staff being also shown in section. Fig. 3 is a view similar to Fig. 2, 65 illustrating the tip adapted for ordinary use. Fig. 4 is a group view illustrating the several parts of the tip about to be assembled. Fig. 5 is a view similar to Fig. 3, 70 illustrating a slight modification of the invention.

Corresponding and like parts are referred to in the following description and indicated in all the views of the accompanying drawings by the same reference characters. 75

In the drawings, the numeral 1 indicates the staff of a crutch, the lower end of which is reduced in diameter as indicated by the numeral 2, and threaded, as indicated at 3. In forming the reduced end 2, an annular 80 shoulder 4 is provided, the purpose of which will presently be made apparent. Also for a purpose to be presently explained, at 5, at opposite sides. 85

The tip embodying the present invention includes a ferrule, indicated by the numeral 6, which, when employed alone, adapts the crutch for use on icy surfaces. The ferrule 6 is tubular and is interiorly threaded at 90 its upper end, as indicated at 7, whereby to adapt it for application to the threaded reduced end of the staff, and it will be apparent that when the ferrule is applied to the staff, its upper end will abut against the 95 shoulder 4 so that, when weight is imposed upon the crutch, the threads 3 and 7 will be relieved of strain, and there will be no danger of the first-mentioned threads, which are of course cut in wood being stripped. In 100 order that the ferrule may readily penetrate snow and ice at its tread end, its said end is interiorly beveled, as indicated at 8, so as to form an annular tread edge 9, which may be sharpened to any extent desired. 105

It will be observed by reference to Fig. 2 of the drawings, that the ferrule is of greater length than the reduced end of the staff, and

the ferrule is formed at diametrically opposite points with openings 10, these openings being formed by cutting inwardly and downwardly and also by cutting directly inwardly, whereby the side and upper walls of the openings will be inclined and their lower walls will be horizontal. It will further be observed by reference to Fig. 2, that the extremity of the reduced end 2 of the staff occupies a plane above that occupied by the lower walls of the openings 10 and that the beveled faces 5 of the said reduced end 2 register with the openings 10. The reason for so proportioning these parts will be pointed out in describing the other elements of the tip. At this point, however, it may be stated, that when the tip is in the condition shown in Fig. 2 of the drawings and is adapted for use on icy surfaces, the tread end of the ferrule will penetrate the ice or snow to a greater or less depth, and, while a quantity of ice or snow will be taken up by the ferrule as the crutch is lifted from the ground, the same will be discharged or forced through the openings 10 as the crutch is again brought to the ground and, consequently, packing of snow and ice in the hollow end of the ferrule is prevented. In this automatic dislodging of the accumulated ice and snow, the beveled faces 5 and the wedge shape of the extremity of the portion 2, play an important part, for as the accumulations are forced upwardly in the ferrule they are divided or broken up by reason of the wedge shape of the beveled end of the said portion 2 and are forced outwardly through the openings by reason of the beveled surfaces 5.

In order that the tip may be adapted for use in summer, or when there is no ice or snow, there is provided a plug 11 preferably of wood, although it may be made of some other material, which is fitted into the open lower end of the ferrule 6 in the manner clearly shown in Fig. 3 of the drawings, and this plug abuts at its upper end against the beveled lower end of the reduced portion 2, and the plug is provided at its lower end with an annular beveled shoulder 12, the beveled side of which abuts against the beveled edge 8 of the said ferrule. There is also provided an anti-slipping tip 13 which is preferably of rubber and which is fitted removably to the lower end of the ferrule 6. The tread portion 14 of the tip 13 rests against the under side of the plug 11 and the tread surface of the said portion 14 may be serrated or otherwise roughened to more effectually provide against slipping. It will now be apparent that when the crutch tip is arranged as shown in Fig. 3, and weight is imposed upon the crutch, the weight will be borne directly by the crutch staff and the ferrule will be relieved of strain to a considerable degree, due to the

fact that the upper end of the plug 11 abuts against the lower end of the staff. It will also be apparent that the flared lower end or beveled portion of the plug, registering with the tread edge 9 of the ferrule 6, prevents this edge from cutting into the tread portion of the rubber tip 13, and that even should the plug 11 be slightly shorter than it should be, the sharp edge of the ferrule will still be prevented from cutting into the rubber tip 13, due to the abutment of the beveled shoulder 12 against the beveled edge portion of the ferrule. Furthermore, it will be apparent that the tip 13 serves as a means for holding the plug 11 in place, and, in the form of the invention shown in Fig. 3, it also serves to cover the openings 10 to prevent the accumulation of dirt in these openings. When it is desired to convert the structure shown in Fig. 3 into that shown in Fig. 2, it is only necessary to remove the tip 13 and then by inserting the finger in one or the other of the openings 10, to remove the plug 11, by pressing downwardly against its upper end, the said upper end of the plug being located in a plane above the lower walls of the openings 10.

In that form of the invention shown in Fig. 5 of the drawings, the flange 12 is cylindrical, as indicated at 15, below its beveled portion, and, it may be desirable to so construct the plug in order to further insure against the cutting of the anti-slipping tip 13. Also, in this form of the invention, the tip is shorter than in the form shown in Fig. 3 and does not cover the openings 10. If found desirable, the plug 11 may be threaded or otherwise removably secured within the ferrule. Also if desired, the tip 13 may be dispensed with as also the plug 11 and a rubber tread tip, approximately of the form of the plug 11, may be provided and removably fitted into the lower end of the ferrule, it being understood, of course, that when such a tip is employed, it will bear at its upper end against the lower end of the staff in the same manner as does the said plug.

Having thus described the invention, what is claimed as new is:

1. A crutch tip having an open lower end and adapted at its upper end to receive the end of a crutch staff, and having an opening in its wall between its said ends.

2. A crutch tip having an open tread end and provided in its wall with oppositely located openings, and means arranged within the tip for dividing accumulations forced upwardly within the tip and for directing such accumulations through said openings.

3. A crutch staff having a beveled lower end and a tip fitted upon the said end of the staff and having an open tread end, and an opening in its wall located opposite the bevel of the said staff end.

4. A crutch tip having an open end, a plug removably fitted therein, and a tread tip removably fitted on to the ferrule and retaining said plug.
5. 5. A crutch tip having an open end, a plug removably fitted in the said end, the tip being interiorly beveled at its said end and the plug being provided with a beveled shoulder abutting against the bevel of the tip end, and a tread tip fitted on to the first-mentioned tip and having its tread portion resting against the lower end of the said plug.
- 10 6. A crutch staff having its lower end cut away, a ferrule fitted on to the said end of the staff and having an opening located opposite the cut away end of the staff, a plug removably fitted in the lower end of the ferrule and abutting at its upper end
- against the lower end of the staff, and a tread tip fitted on to the ferrule and having its tread portion resting against the lower end of the plug.
7. In a crutch, a staff, a tubular open ended ferrule, the staff being fitted into the upper end of the ferrule and the ferrule being provided in its wall with an opening located at the extremity of the inserted end of the staff, and means for closing the open end of the ferrule, the said means being removable.
